COMBINED ROPE CLAMP AND BLOCK

Manuel D. Silva, Hayward, Calif.

Application February 3, 1959, Serial No. 54,434

Term of patent 14 years

(Cl. D41—1)

I claim:

The ornamental design for a combined rope clamp and block, substantially as shown.
